DESIGN FOR A GLOVE

Charles R. Kovar, Richmond Hill, N. Y., assignor to Julius Kayser & Co., New York, N. Y., a corporation of New York

Application June 27, 1936, Serial No. 63,530

Term of patent 3½ years

To all whom it may concern:

Be it known that I, Charles R. Kovar, a citizen of the United States, residing at 102-32 Park Lane South, Richmond Hill, Long Island, in the city of New York, county of Queens, and State of New York, have invented a new, original, and ornamental Design for a Glove, of which the following is a specification, reference being had to the accompanying drawing, forming part thereof.

Figures 1 and 2 are respectively a front view and a back view of a glove embodying my new design.

The entire glove is of ribbed fabric, the texture of which is shown in the drawing. A cuff is formed by an extension of the glove which is folded back toward the wrist portion; the cuff being divided on the back as shown in Figure 2 and held under a button.

I claim:

The ornamental design for a glove, as shown and described.

CHARLES R. KOVAR.
